ELECTRICAL CONNECTOR

William S. Chickvany, Norwalk, Conn., assignor to
Burndy Corporation, a corporation of New York
Filed May 22, 1958, Ser. No. 737,142
2 Claims. (Cl. 174—84)

My invention relates to electrical connectors having tubular bodies that may be used to splice wires or cable and, more particularly, to electrical connectors of the type that are indented to the wire and locked thereto and covered by an electrical insulating material.

Hitherto in actual practice electrical connectors having tubular bodies used to splice wires or cables have been connected to the cable and then insulated by the application of insulating tape or sleeves. Moreover, it has been common practice on occasion to incorporate within the electrical connector an oxide inhibiting compound. It has been found that when such a compound is included within the connector and the connector then indented or crimped onto a cable, the oxide inhibiting compound has a tendency to be extruded from the connection. Moreover, in the past difficulty has been encountered in making the connection because it was necessary to hold the conductor within the sleeve and make the indent simultaneously.

One of the objects of my invention, therefore, is to provide an electrical connector having a tubular body for splicing a wire or cable and having means for retaining the oxide inhibiting compound within the connector body during installation.

Another object of my invention is to provide an electrical connector which may be indented or crimped onto a wire or cable and which would result in a completely insulated connection.

A further object of my invention is to provide an insulated electrical connection which is fully water-repellant when connected to an electric cable.

Still another object of my invention is to provide an electrical connector having means for retaining the conductor within the connector while the indent is made.

One of the features of my invention is the provision of an electrical connector having a tubular metal body over which is disposed coaxially an insulating sleeve made of a material capable of substantially transmitting the forces necessary for crimping the metal body to an inserted conductor. Oxide inhibiting compound is disposed within the tubular body and end caps are provided to prevent the loss of the compound during installation of the connector. Each of the end caps is provided with a weakened central section through which the bared conductors may be inserted to have the tubular metallic body crimped thereto. The caps are composed of a material which is resilient and has an elastic memory so that the caps will be disposed adjacent to electrical conductor forming a water-repellant seal and containing the oxide inhibiting compound within the tubular connector. Moreover, the caps tend to restrain the conductor from pulling out of the connector until the installation is completed.

These and other features and objects of this invention will become more apparent by reference to the following description taken in conjunction with the accompanying drawings, in which:

FIG. 1 is an exploded view in perspective of the electrical connector of my invention;

FIG. 2 is a cross sectional view of the electrical connector of my invention; and

FIG. 3 is an enlarged cross sectional view of the same taken in the plane 3—3 of FIG. 2.

In the drawings reference numeral 10 designates a tubular body or sleeve composed of a malleable metal

2

such as aluminum or copper. The diameter of the internal bore of the sleeve is sufficient to permit the bared conductor 12 to be inserted therein. A cable stop 14 may be formed in the bore of the sleeve 10 to prevent inserting the cable too far. An insulating tube 16 is disposed in coaxial relation to the metal sleeve 10. The insulation tube or sleeve 16 has a bead 18 formed in the center and the metal sleeve 10 has a depression 20 rolled in its outer wall. Locking the bead 18 in the depression 20 prevents longitudinal movement of the insulating tube 16 relative to the metal tube 10. Obviously, other methods of preventing relative movement may be used such as friction-fitting the tube 16 within the insulating sleeve 16 or utilizing adhesives or cement that are well known in the art. The insulating sleeve may be made of any well known insulating material such as nylon, copolymers of vinyl chloride-vinyl acetate or saran, any of which is capable of withstanding the compression forces of indenting as hereinafter explained.

20 An oxide inhibiting compound 22 is disposed within the bores of the metal sleeve 10 and caps 24 and 26 are utilized to retain the compound therein. The cap 24 is friction-fitted to the inside of the overhanging portion 28 of the insulating sleeve 16. The cap 24 has a central weakened section 30 of thinner material than the remainder of the cap. The cap 26 is an alternate embodiment and is shown fitted to the outside of the overhanging portion 32 of the insulating tube 16 and is retained thereon by disposing the bead 34 within the depression 36 of the insulating tube 16.

25 In use an insulated wire has its conductor portion 12 bared and inserted through the thin portion of the cap. The cap is preferably made of a material which has an elastic memory so that the broken or torn section of the cap 42 would tightly grip the insulation 38 of the wire. The conductor is retained within the sleeve 10 due to this gripping action. To assist in the insertion of the bared end of the wire 38, the malleable tube 14 is chamfered. The caps 24 and 26 may be color coded 30 to indicate the size wire for which the connector is designated. As shown at 40, as the conductor 12 is inserted within the bore and the oxide inhibiting compound 22 is extruded around the conductor 12 toward the opening of the connector but is retained therein by the cap 26. 35 Moreover, the gripping by section 42 of the cap 26 around the insulation 28 of the wire 38 prevents the entrance of drops of moisture, preventing corrosion of the conductor and the connector. This action is aided and abetted by the extrusion of the oxide inhibiting compound 40 around the wire to fill the spaces in the bore. After the conductor is disposed in the bore of the sleeve 10, indentations or crimps 44 are made by suitable tools thru the insulating sleeve 16 to join the metal sleeve 10 to the conductor 12. Naturally, the insulation must be of a 45 material which is capable of withstanding the indentation without substantially deleterious effects. Moreover, the insulating sleeve must transmit the indenting force to the sleeve 10 to pressure forge the connector and conductors.

50 I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained and new results accomplished, as it is obvious that the particular embodiments herein shown and described are only some of the many that can be employed to attain these objects and accomplish these results.

I claim:

1. An electrical connection comprising: a malleable metal tube including an internal base; an insulating sleeve disposed around said metal tube, an end of said insulating sleeve extending beyond an end of said metal tube; means securing said insulating sleeve to said metal tube against relative longitudinal movement therewith; said sleeve made of a material having the physical characteristic of transmitting indenting forces transversely therethrough without rupture; an insulating cup shaped closure secured against relative longitudinal movement to and sealing said end of said sleeve; said cup shaped closure including an end portion having a central weakened section of reduced thickness; said cup shaped closure made of a material having the physical characteristic of resiliency; said central weakened section of reduced thickness having the physical characteristic of being penetrable by a conductor thrust thereagainst; an insulated electrical conductor including an end length of bare conductor; said bare conductor end length disposed in said tube internal bore; said tube internal bore indented to said bare conductor end length; said insulated conductor disposed through said insulating cup shaped closure weakened section; said cup-shaped closure resiliently grasping said insulated electrical conductor and securing said insulated electrical conductor against relative longitudinal movement in the direction of the removal of said conductor from said base and forming a seal around and with said insulated electrical conductor.

2. An electrical connector for joining a pair of insulated electrical conductors, each of said conductors having a bared end of conductor from which the insulation has been removed comprising: a malleable metal tube including an internal bore; an insulating sleeve disposed coaxially around said metal tube, an end of said insulating sleeve extending beyond an end of said metal tube; means securing said insulating sleeve to said metal tube against relative longitudinal movement therewith; said sleeve being composed of a material having the physical characteristic of transmitting indenting forces transversely

therethrough without rupture; an insulating cup shaped closure cap secured against relative longitudinal movement to and sealing said end of said sleeve; said cap including an end portion having a central weakened section of reduced thickness; said cap having the physical characteristic of elasticity; said central weakened section having the physical characteristic of being penetrable by said insulated conductor thrust thereagainst; said cap when penetrated by a thrustthrough insulated conductor having the physical characteristics of grasping said conductor against relative longitudinal movement in the direction opposite to the direction in which the conductor was inserted, and of forming a seal around the insulation of said conductor, said cap secured to said sleeve by a force at least equal to the force exerted by said cap against a thrustthrough conductor.
